DESIGN FOR AN AIRPLANE HANGAR

Dwen R. Younger, San Francisco, Calif.

Application May 23, 1947, Serial No. 139,233

Term of patent 14 years

(Cl. D13—1)

To all whom it may concern:

Be it known that I, Dwen R. Younger, a citizen of the United States, residing at San Francisco, in the county of San Francisco and State of California, have invented a new, original, and ornamental Design for an Airplane Hangar, of which the following is a specification, reference being had to the accompanying drawing, forming part thereof, in which:

Fig. 1 is a front perspective view of an airplane hangar showing my new design.

Fig. 2 is a front perspective view with the door in an open position.

Fig. 3 is a front elevational view.

Fig. 4 is a side elevational view, and

Fig. 5 is a top plan view.

I claim:

The ornamental design for an airplane hangar, substantially as shown.

DWEN R. YOUNGER.
